United States Patent Office

Des. 195,726
Patented July 23, 1963

195,726

HAT RACK CABINET

David Harper, 2122 Webster Ave., Pittsburgh, Pa.

Filed May 18, 1962, Ser. No. 70,197

Term of patent 14 years

(Cl. D33—19)

FIG. 1.

FIG. 2.

FIG. 3.

FIG. 4.

FIGURE 1 is a top plan view of a hat rack cabinet showing my new design;

FIGURE 2 is a perspective view looking from the front right-hand side of the cabinet;

FIGURE 3 is a front elevational view of said cabinet, FIGURE 3 illustrating the front closure doors in their open position; and

FIGURE 4 is a perspective view taken from the left-hand side thereof.

The back of the cabinet is plain.

I claim:

The ornamental design for a hat rack cabinet, as shown and described.
